DESIGN FOR A COMBINATION WALLET, COSMETIC CONTAINER, CHANGE PURSE, AND TRANSPARENT POCKET

Rita B. Bach, New York, N. Y.

Application May 31, 1943, Serial No. 110,332

Term of patent 14 years

To all whom it may concern:

Be it known that I, Rita B. Bach, a citizen of the United States and a resident of the city of New York, in the county of New York and State of New York, have invented a new, original, and ornamental Design for a Combination Wallet, Cosmetic Container, Change Purse, and Transparent Pocket, of which the following is a specification, reference being had to the accompanying drawing forming a part thereof.

Fig. 1 is a front view in closed position of a combination wallet, cosmetic container, change purse and transparent pocket showing my design.

Fig. 2 is a rear view thereof.

Fig. 3 is a perspective view showing the wallet in open position.

I claim:

The ornamental design for a combination wallet, cosmetic container, change purse, and transparent pocket, substantially as shown.

RITA B. BACH,
